(57) **CLAIM**

The ornamental design for an electroporation processing assembly, as shown and described.

DESCRIPTION

FIG. 1 is a front, top, right perspective view of an electroporation processing assembly, showing the new design; FIG. 2 is a rear, bottom, left perspective thereof; FIG. 3 is a left view thereof;

FIG. 4 is a rear view thereof;

FIG. 5 is a front view thereof;

FIG. 6 is a top view thereof; and,

FIG. 7 is a bottom view thereof.

The broken lines of even length depict portions of the electroporation device that form no part of the claimed design.
